UNITED STATES PATENT OFFICE.

MARY E. BRATTIN, OF OAKLAND, CALIFORNIA.

COMBINED WASHTUB AND HEATER.

933,954.

Specification of Letters Patent. Patented Sept. 14, 1909.

Application filed October 29, 1908. Serial No. 460,112.

To all whom it may concern:

Be it known that I, MARY E. BRATTIN, a citizen of the United States, residing at Oakland, in the county of Alameda and State of California, have invented certain new and useful Improvements in Combined Wash-tubs and Heaters, of which the following is a specification, reference being had therein to the accompanying drawing:

10 My invention relates to a novel combination of a wash tub and a heater, and the primary object thereof is to assemble the elements in such relation that the water in the tub may be quickly heated to boiling, and 15 in this manner accelerate the washing of clothes, when, as frequently is the case, hot water is not readily available.

Another object of the invention is to simplify the construction and arrangement of 20 the organization so that the same may be installed with facility in any convenient place where there is ready access to fuel.

To the accomplishment of the recited objects, and others coördinate therewith, the 25 preferred embodiment of my invention resides in that construction and arrangement of parts hereinafter described, illustrated in the accompanying drawings, and embraced within the scope of the appended claims.

30 In said drawings:—Figure I is a sectional elevation of the wash tub, the heater, and flue, and Fig. II is a longitudinal section of the wash tub and heater removed.

Referring more particularly to the drawings for a detail description of my invention, the numeral 5 designates a stationary wash tub constructed of corrugated boiler-iron, and equipped with a pair of faucets (6). Heat may be applied to the tub in 35 various ways, but in the present instance, a drum will be of suggestive scope sufficient to afford full explication of the principle of my invention. This heating drum (7), as clearly exhibited in transverse section in Fig. 40 I of the drawings is of trapeziform and has a cover or lid (8) hinged at 9, the said drum and cover being lined throughout with suitable heat resisting material (10), such for example as asbestos. Furthermore, the heating 45 drum is made large enough to inclose the wash tub, the sides of which converge

55 abruptly to form a space (11) to insure a thorough radiation of the heat. The rear side of the heating drum is supported in a recess (12) having the contour of a scalene triangle and being formed in the wall (13), which has a main flue (14) and a ramified flue (15) communicating with the interior of the heating drum.

60 Beneath the arrangement hereinbefore described is located a heater pipe (16) carrying the burners (17) and interjacent valves (18), and connected with any suitable source of gas supply, the said burners extending through the open portion of the drum and 65 occupying a position in proximity to the bottom of the tub.

70 In use, water is admitted to the wash tub (5), which, it will be assumed, contains the soiled clothes. The lid (8) is then closed and the burners (17) lighted, causing the heated air to circulate around the tub in space (11) and eventually making its exit through the egress flue (15) into the main flue (14). Owing to the relative disposition 75 of the tub and the heating drum and the resultant area of the former that is subjected to the action of heat radiation, in a comparatively short time the water will be in a state of ebullition. In operation the lid (8) 80 serves in a dual capacity as a cover for both the wash tub and the heating drum.

Having thus described my invention what I claim as new is:—

1. The combination with a wall having an 85 inclined recess and a flue therein, of a heating drum having a quadrilateral contour, the rear side of said heating drum adapted to lie contiguous said recess so as to support the drum at right angles to the wall, a wash 90 tub inclosed by said drum, said tub converging downwardly to form a space to permit radiation of the heat from the walls surrounding it and allow circulation of the heated gas, and said wall having a communicating passage from the drum to the flue.

95 2. The combination with a wall having an inclined recess and a flue therein, of a heating drum having a quadrilateral contour, the rear side of said heating drum adapted to lie contiguous said recess so as to support 100

the drum at right angles to the wall, a wash tub inclosed by said drum, said tub converging downwardly to form a space to permit radiation of the heat from the walls surrounding it and allow circulation of the heated gas, said wall having a communicating passage from the drum to the flue, a cover common to said heating drum and

tub, the bottom of said drum being open, and burners disposed through said opening.

In testimony whereof I hereunto affix my signature in presence of two witnesses.

MARY E. BRATTIN.
